United States Patent Office.

JULIUS HERRIET, OF NEW YORK, N. Y., ASSIGNOR TO DAVID WOLFE BRUCE,
OF SAME PLACE.

Design No. 2,578, dated February 12, 1867.

DESIGN FOR PRINTERS' TYPE.

The Schedule referred to in these Letters Patent and making part of the same.

TO ALL WHOM IT MAY CONCERN:

Be it known that I, JULIUS HERRIET, of the city of New York, in the county of New York, and State of New York, have originated and designed a new Pattern for Printing Types, which I call Rustic Ornamented Shaded capitals, points, and figures, reference being had to annexed printed impression thereof. It differs from every other kind of type in style, shape, and proportion.

What I claim as my invention, and desire to secure by Letters Patent, is—

The design or pattern for printing types herein set forth.

JULIUS HERRIET.
